COMBINED SITZ BATH

Filed Nov. 20, 1928

2 Sheets-Sheet 2

UNITED STATES PATENT OFFICE

JOHANN WENISCHNIGER, OF GRAZ-EGGENBERG, AUSTRIA

COMBINED SITZ BATH

Application filed November 20, 1928, Serial No. 320,562, and in Austria November 26, 1927.

This invention relates to a collapsible portable bath which, owing to its peculiar construction, possesses all advantages of a complete bath and in spite thereof takes up very small space only and is not heavier than a sitz-bath. Essentially these advantages are attained in that the bath consists of a sitz-bath which is connected with a water-supply device, arranged outside the bath and provided with operating members disposed outside the bath in such a manner, that they can be handled by the bather; adjustable supply members being connected with the water-supply device for leading the water by way of a rose or the like back into the bath or into the sink. According to the present invention the bath is further provided with a back adapted to be turned down and to be adjusted and fixed in a vertical or inclined position to act as back-rest and in a horizontal position in order to be used as seat.

In view of this construction the bath can be used as a comfortable sitz-bath with a simultaneous spraying of the upper part of the body and a heated back, as foot-bath and standing as shower-bath. After use the water is discharged from the bath by means of a pump and the entire device can be collapsed and stored in a small case.

One mode of carrying out the present invention is illustrated by way of example on the accompanying sheets of drawings in which

Fig. 1 shows the bathing device in use as sitz-bath; while

Figs. 2 and 3 illustrate different modes of using the bathing device.

Fig. 4 shows the device in the collapsed or folded condition, and

Fig. 5 is a sectional view of the connection between the back-rest and the bath.

In the drawings, 1 designates the bath, 2 a wooden rest, 3 a foot-rest, 4 a pump, 5 a back-rest, 6 a rose, 7 the supply tube and 8 hand levers, preferably arranged at the longitudinal walls of the bath.

The bath 1 is suited to a man of medium height (5 feet 9 inches). The bath can be adapted to men of larger or smaller height by adjusting the length 9 of the foot rest.

If desired it can be manufactured in various sizes.

The shape is such that a person can comfortably sit in the bath and does not displace the entire water, so that sufficient room is left for a sufficient water-surplus. This condition is particularly satisfied by a suitable width of the bath.

When entering the bath one side or both sides of the latter can be used as support without the danger that the bath moves or is upset.

The sheet metal floor of the bath 1 rests on a wooden rest 2, the broad side 10 of which rests on the floor of the room. Thus it is attained that, firstly the floor of the bath and the bath itself cannot be damaged if even a very heavy person stands up in the same, secondly the bath cannot be damaged from outside if it is placed on a sandy or uneven ground (for instance in summer when taking a sun-bath in the garden) and thirdly the edge of the bath cannot damage for instance the linoleum in kitchens.

During the bathing, either by operating one of the hand-levers 8 or the foot-rest 3, water can be pumped through the tube 7 and the same may be passed over the upper part of the body, whereby the sitz-bath approaches a full bath.

On its way from the pump to the rose, the water passes through the hollow back-rest 5, the latter being heated thereby to the temperature of the water, so that the back of the bather does not lean against a cold sheet metal.

By lateral protecting walls 11 and an extension 12 the back 5 is of such a shape, that the water running down the back of the bather or the back-rest cannot run over the edge of the bath or the edges of the back-rest onto the floor but the whole water is returned into the bath.

If the sitz-bath according to Fig. 1 is ready, the upper edge of the back-rest is slightly moved forward, whereby the two hooks 13 of the bar 28 (Fig. 5) are disengaged. Now if the back-rest is released, the bolts 14 of the extensions 15 of the back-rest slide in guide-slots 16 and thereby the back-rest moved

down automatically and, owing to the provision of supporting bars 17, 18 and the hinge

19, forms a firm seat (Fig. 2). Now for instance while sitting on the warm seat the body can be dried with a towel or the like, while the feet are still in water.

By the use of a tube-holder 21 the water can be allowed to run down the back or a shower-bath can be taken without the help of another person (Fig. 3). When taking a bath of this kind, the foot-rest 3 can be disconnected from the means operating the pump. When taking shower-baths it is of advantage to use the long hand-lever shown in Fig. 3. After having taken a bath, the end of the tube is placed into the sink (at the right hand side of Fig. 1) and the bath is pumped empty. The empty bath can be folded in such a manner, that it can be placed in a casing or box of a length of 30", a height of 26", and a width of 16" measured at the inside of the box, so that it can be readily stored in any room (Fig. 4). In this case the back-rest 5 is turned out of the horizontal position for 90 degrees and does not extend beyond the bath.

In the construction shown in Fig. 5, the edge of the bath consists of a single length of angle-iron 24 with semi-tubular frames 25 between which the end of the sheet-metal 26 is disposed. The frames are secured by rivets 27. At the riveting places the semi-tubular frames are filled with material in order to provide a safe hold for the rivets.

35 The pump 4 is constructed in such a manner, that its manufacture is simplified without impairing its durability and operation, this being accomplished by the use of a piston with rubber ring.

40 In order to manufacture the bath according to the present invention on a large scale and at low costs, the bath, pump and frame are manufactured separately and can be easily fitted up and again taken to pieces.

45 The bathing device according to the present invention is a high class substitute for a complete bathing device and is well suited for different water-cures, without the bather requiring the help of another person. Therefore the same is particularly well suited for the treatment of invalids at home and as bath for children.

What I claim is—

50 1. Collapsible portable bathing device comprising in combination a sitz-bath, a hollow back-rest movably secured to the latter so as to be adjusted and fixed in any desired position, a water supply device arranged outside the sitz-bath, means connecting the water supply device to the sitz-bath, means for operating the former arranged outside the sitz-bath, an adjustable water conduit passing from the water supply device to the hollow back-rest, a tube leading away from the

latter, and a rose secured to the end of the said tube.

2. A collapsible portable bath apparatus consisting of a tub arranged for a seated bather, a back rest on said tub, shower attachment over said tub, a pump and lever operating means for the pump attached to the outside of said tub, said lever operating means comprising at least one hand lever operable by a person sitting in said tub, and a foot rest outside of said tub, said foot rest having means to attach the same to said levers to form operable connections therewith and capable of operating said pump.

3. A bathing apparatus as in claim 2 where-
in said back rest is attached to said tub by
means permitting it to be held in a slanting
position to serve as a back rest, in a hori-
zontal position to the outside of the tub to
serve as a seat, and in a vertically downward
position to save storage space.

4. An apparatus as in claim 2 wherein
said back rest is hollow and wherein a hose
connects the part of said back rest which is
nearest the pump with said pump, and where-
in a second hose connects the other end of said
back rest to said shower attachment, whereby
said hollow back rest serves as a conduit for
water from said pump.

5. An apparatus as in claim 2 wherein said
back rest has means allowing it to be adjusted
to a horizontal position as well as to a slant-
ing position, and wherein the end of said
back rest adjacent the top of said tub over-
laps said tub when said back rest is in a
slanting or horizontal position, so that water
on said back rest tends to flow into said tub.

6. An apparatus as in claim 2 wherein said
back rest has a raised portion along the side
and top thereof to prevent water from flow-
ing in a direction other than towards said
tub.

In testimony whereof I affix my signature.
JOHANN WENISCHNIGER.
